UNITED STATES PATENT OFFICE.

WADE H. WINEMAN, OF CHICAGO, ILLINOIS, ASSIGNOR TO SULLIVAN MACHINERY COMPANY, A CORPORATION OF MASSACHUSETTS.

SEPARATOR.

Application filed July 29, 1919. Serial No. 314,103.

To all whom it may concern:

Be it known that I, WADE H. WINEMAN, a citizen of the United States, residing at Chicago, in the county of Cook and State of Illinois, have invented certain new and useful Improvements in Separators, of which the following is a full, clear, and exact specification.

My invention relates to separators.

It has for its object to provide an improved separator especially adapted to the separation of gas and liquid, whereby the capacity and efficiency of the same is increased at the same time that the construction is simplified. A further object of my invention is to provide an improved separator especially adapted to use in gas and liquid separating or pumping systems or air lift systems and adapted to separate the several elements of the material to be separated in a more efficient manner, and to utilize the momentum of the material to be separated, as for instance, the discharge of a well, in discharging the material therefrom and as a propulsion force in the line, at the same time that a more simple and less expensive construction of the separator and its cooperating system is made possible. These and other objects and advantages of my improved construction will, however, hereinafter more fully appear.

In the accompanying drawings I have shown for purposes of illustration one embodiment which my invention may assume in practice, the same being illustrated as applied to an air lift system.

In these drawings,

Fig. 1 is a diagrammatic side elevation, partially in section, of such a system equipped with my improvement.

Fig. 2 is a detail plan view of the separator, the same being shown in a position turned 180° about its axis relative to Figure 1.

Fig. 3 is a detail side elevation of the separator when looking from left to right at the structure shown in Fig. 2.

In this illustrative construction I have shown an air lift system including the usual compressor 1 having a discharge pipe 2 connected to a receiver 3 and the latter connected, through a pipe 4, to a down pipe 5 of an air lift pump 6 disposed in the well casing 7, and discharging the mixture of air and liquid formed thereby, through an up

pipe 8 which is connected to improved separating mechanism, hereinafter described, which operates to separate the air from the liquid and supply the liquid to a line discharge pipe 9 leading to an elevated separator tank 10, and thence through another discharge pipe 11, which may lead to the line, or itself form the line.

In my improved construction it will be observed that the up pipe 8 is connected through a long sweep elbow 12 to a booster casing 13, herein cylindrical in form and closed at both ends, the elbow 12 communicating with an inlet member 14 substantially tangentially arranged at the top of the booster casing 13 and communicating with the interior of the casing through an opening 15 in the outer wall thereof. It will be observed that the entire interior of the cylindrical booster casing 13 is free from obstruction, so that the stream of air and liquid delivered to the same through the inlet opening 15, may rotate freely therein without interruption of its flow. More particularly, it will be observed that when air and liquid is thus delivered at the periphery of the casing, the heavier element, i. e. the liquid, will tend to follow a path close to and spirally around the inner wall of the casing, while the lighter element, i. e. the air, will tend to occupy the space enclosed by the rotary stream of liquid. In other words, it will be observed that through my improved construction it is possible to utilize the momentum of the inflowing supply to obtain a very effective separation of the same into its constituents.

After the elements have thus been separated, they leave the booster casing through different paths. We will first consider the liquid. It will here be observed that I have provided at the bottom of the casing, to which the still rotating stream of separated liquid gravitates, an outlet opening 16 substantially like the inlet opening 15, and an outlet member 17 substantially like the inlet member 14 and similarly located at the periphery of the booster casing in such a manner as to provide an outlet which enables the discharge of the rotating stream of liquid, without interrupting its flow, and one which thereby also enables the force of the inflow, herein the flow from the well, to be utilized as a motive force expelling the liquid from the separator. As shown, the outlet mem-

ber 17 is herein also connected with the discharge pipe 9, a swing check valve 18 and a gate valve 19 preferably being provided in the pipe 9 closely adjacent the separator, and 5 the discharge pipe 9 is in turn connected to a riser 20 leading to an umbrella separator 21 in the separator tank 10, which as heretofore described communicates with the desired point of discharge through the pipe 10 11, the valves 18 and 19 acting to prevent back flow from the tank or to enable the discharge to be cut off when desired. Here, attention is also directed to the fact that a suitable drain pipe 22 having a usual drain 15 cock 23 therein, is connected to the bottom of the separator casing and carried over and extended into the well casing 7 so that the separator casing and those parts of the system connected therewith may be drained 20 back into the well whenever desired, as for instance, when it is desired to prevent freezing.

Referring to the air separated from the liquid and disposed in the center of the rotating stream of liquid, in my improved construction it will be observed that an air pipe 24 is connected, as by threading, in a plate 25 provided on the top of the separator casing, and that this air pipe communicates 30 with an axially located aperture or outlet 26 provided in the top of that casing, through which aperture the accumulated air passes up into the pipe. As shown, the pipe 24 is provided with a T 27 connecting the same to 35 another pipe 28, which may, if desired, communicate either with the atmosphere or by means of a second T with another pipe 29 connected thereto and leading to the intake 30 of the compressor, depending upon the adjustment 40 of valves 31 and 32 disposed in the pipes 29 and 28, respectively. As shown, the pipe 24 is also herein provided with a swing check valve 33 to prevent back flow and an adjustable pressure controlling globe valve 34 controlling the boosting pressure in the casing 45 and adjustable to maintain a constant liquid discharge therefrom by varying the air discharge and the resultant water level in the casing. Herein it will be noted that these 50 valves are provided in the pipe 24 at points adjacent its connection to the pipe 28, and that the pipe 24 is extended laterally therefrom to a point beneath the riser 20, where it is provided with a riser 35 extending into the 55 riser 20 and carrying on its upper end a pump or auxiliary jet 36 adapted to again mix the air in the column of liquid flowing through the riser, and thereby increase the lift obtainable, the air again being separated 60 from the water by the umbrella 21 in the separator tank 10. Here, it will also be observed that upon the separator casing I preferably provide a pressure gauge 37, and that in the pipe 4 controlling the air supply from the compressor I preferably provide a

regulation cock 38 and a pressure gauge 39, in order that the pressure in the various parts of the system may be readily determined and that the pressure from the receiver may be supplied as needed.

70

In the operation of my improved system, it will be observed that the flow of the liquid from the well is continuous, as distinguished from those prior constructions utilizing booster separators wherein it has been necessary heretofore to bring the liquid to a standstill in the booster. As a result, it will be observed that I am able to conserve the discharge from the well and utilize the same to a large extent as a propulsion force 75 acting, not only to separate the parts of the mixture more effectively and efficiently, but also to assist the pressure in the separator casing in propelling the separated liquid 80 through the discharge line, thereby materially increasing the capacity of an installation having a given air supply. It will also be noted that through my improved means for separating the elements of the mixture it is possible completely to separate 85 these elements, the air discharged from a separator of my improved construction being dry and the liquid discharged being free from air in suspension, features which not only increase the efficiency of the system but entirely eliminate all of those very trying difficulties heretofore experienced arising from air locks, i. e. the accumulation 90 in high spots in the line of air carried in suspension in the liquid. The applicability of the applicant's mechanism as a separator for pumping systems will be most clear when it is considered that for a normal pumping operation under a normal pumping pressure the percentage of air by volume 95 of the mixture entering the separator would be in the general neighborhood of 75 or 80 per cent. Of course this figure would depend upon the pressure within the booster and other considerations. It does show, however, the enormous amount of gas which must be handled and which is handled in a manner never before handled in a pumping system separation means. Attention is also directed to the fact that through my 100 improved construction it is possible to eliminate entirely any necessity for apparatus within the separator, thereby materially reducing the cost of the installation and removing any necessity for the adjustment 105 of such mechanism as has heretofore been necessary. In this connection, attention is also directed to the fact that through the provision of the long sweep elbow inlet leading 110 to the separator it is possible readily to remove this elbow, and thereby permit convenient backblowing, cleaning, etc. of the well without in any way interfering with the booster or the piping thereon. These 115 and other advantages of my improved con-

struction will, however, be clearly apparent to those skilled in the art.

While I have in this application specifically described one embodiment which my invention may assume in practice, it will be understood that this form of the same is used for illustrative purposes, and that the invention may be modified and embodied in other forms and adapted to other uses 5 without departing from its spirit or the scope of the appended claims.

What I claim as new and desire by Letters Patent to secure is:

1. In a gas and liquid separator system, 15 gas lift means for supplying a stream of gas and liquid mixture, cooperating centrifugal separating means operated by said stream, and means for thereafter returning one of said mixture constituents to said supply means.

2. A gas and liquid separating system comprising gas-lift means for providing a moving mixture of gas and liquid, and centrifugal gas and liquid separating means 25 operated thereby and without interruption of the liquid flow, having separate outlets for the constituents of said mixture.

3. In combination, a gas-lift pump, a discharge line, and a centrifugal gas and liquid 30 separator therebetween operated by the pump discharge without counter flow of liquid therein.

4. An air lift system comprising an air lift pump, and a centrifugal separator receiving the discharge therefrom and operated by the momentum of said discharge without interruption of liquid flow therein.

5. An air lift system comprising an air lift pump, and a centrifugal separator receiving the discharge therefrom and operated by the momentum of said discharge and having an outlet through which the separated liquid is propelled by the momentum of said discharge.

45 6. A booster comprising a casing having a lateral outlet opening and an unobstructed interior operative to produce a rotating stream of mixture therein and a communicating outlet opening, and pressure regulating means for maintaining a constant discharge through the latter.

7. Air lift mechanism comprising an air lift pump, and a centrifugal separator receiving the discharge therefrom and operated by said discharge.

55 8. In a liquid pumping system, means directing a stream of mixed gas and liquid, and cooperating gas and liquid separating means comprising a centrifugal separator receiving the discharge from said means and operated by said discharge.

60 9. Air lift mechanism comprising an air lift pump, and a centrifugal separator receiving the discharge therefrom and having tangential inlet and outlet openings.

10. Air lift mechanism comprising an air lift pump, and a centrifugal separator receiving the discharge therefrom and having tangential inlet and outlet openings and an axial air outlet.

70 11. Air lift mechanism comprising an air lift pump, and a substantially cylindrical casing having a tangential inlet receiving the pump discharge and a separate outlet for the pumped liquid.

75 12. Air lift mechanism comprising an air lift pump, and a substantially cylindrical casing having a tangential inlet receiving the pump discharge therefrom and a separate outlet for the pumped liquid, said liquid outlet likewise being tangentially disposed.

80 13. Air lift mechanism comprising an air lift pump, and a substantially cylindrical casing having a tangential inlet receiving the pump discharge and a separate outlet for the liquid, said liquid outlet likewise being tangentially disposed and at the opposite end of said casing from said inlet.

85 14. Air lift mechanism comprising an air lift pump, and a substantially cylindrical casing having a tangential inlet receiving the pump discharge and cooperating tangentially and axially disposed liquid and air outlets.

90 15. In an air lift system, an air lift pump having a discharge, a centrifugal separator having a tangential inlet, and a removable elbow section in said pump discharge communicating with said inlet.

100 16. An air lift system for wells comprising an air lift pump disposed in the well, a centrifugal separator receiving the discharge therefrom and operated by said discharge, and means for draining said separator into the well.

105 17. An air lift system comprising an air lift pump, a centrifugal separator receiving the discharge therefrom and operated by said discharge without interruption of liquid flow, a tank receiving the liquid discharged from said separator, and means for controlling the flow between said separator and tank.

110 18. An air lift system comprising an air lift pump, a centrifugal separator receiving the discharge therefrom and operated by said discharge without interruption of liquid flow, a separator tank, a liquid discharge line from said separator, an auxiliary jet in said line, and means for supplying air thereto from said separator.

115 19. In an air lift system, an air lift pump, a centrifugal separator having tangential inlet and discharge openings, said inlet opening being connected with said air lift pump, and a line connected to said discharge opening for conducting liquid to a point of use, said centrifugal separator providing for discharge of said liquid to said discharge line without counterflow of liquid.

120

130

135

140

145

150

20. In an air lift system, an air lift pump, a centrifugal separator receiving the discharge therefrom, and a discharge line leading to a point above said centrifugal separator and communicating with the latter through a connection tangential thereto whereby the centrifugal force of the liquid circulating in said separator increases the possible lift of said liquid in said discharge line.
21. In an air lift system, an air lift pump, a centrifugal separator receiving the discharge therefrom, and a discharge line leading to a point above said centrifugal separator and communicating with the latter through a connection tangential thereto whereby the centrifugal force of the liquid circulating in said separator increases the rate of flow in said discharge line.
22. In an air lift system, an air lift pump, a centrifugal separator with which said pump communicates through a tangential opening, said opening being arranged adjacent the top of said separator, a discharge line communicating with said separator through a tangential opening adjacent the bottom of said separator and leading to a point above said separator, whereby on supply of liquid to said air lift pump the discharge of liquid through said discharge line will be effected by the combined forces of centrifugal force, gravity, and the pressure in said separator.
23. In a liquid pumping system, means for supplying a stream of mixed gas and liquid, and cooperating gas and liquid separating means operated by the movement of said liquid therein and guiding the liquid in a smooth flow from its inlet thereto to its point of discharge therefrom and having separate outlets for said gas and liquid, the latter arranged substantially in the direction of the instantaneous direction of the liquid flow at its instant of discharge.
24. In a liquid pumping system, means for supplying a stream of mixed gas and liquid, cooperating gas and liquid separating means operated by the movement of said liquid therein and guiding the liquid in a smooth flow from its inlet thereto to its point of discharge therefrom and having separate outlets for said gas and liquid, the latter arranged substantially in the direction of the instantaneous direction of the liquid flow at its instant of discharge.
25. In a liquid pumping system, means for supplying a stream of mixed gas and liquid, cooperating gas and liquid separating means operated by the movement of said liquid therein and guiding the liquid in a smooth flow from its inlet thereto to its point of discharge therefrom and having separate outlets for said gas and liquid, the latter arranged substantially in the direction of the instantaneous direction of the liquid flow at its instant of discharge, and means for restricting the escape of the gas to prevent loss of liquid propulsion capacity, the inlet of the mixed stream to said separating means being located higher than the liquid outlet.
26. In a liquid pumping system, means for supplying a stream of mixed gas and liquid, cooperating gas and liquid separating means operated by the movement of said liquid therein and guiding the liquid in a smooth flow from its inlet thereto to its point of discharge therefrom and having separate outlets for said gas and liquid, the latter arranged substantially in the direction of the instantaneous direction of the liquid flow at its instant of discharge, and means for restricting the escape of the gas to prevent loss of liquid propulsion capacity, said last mentioned means being adjustable to maintain a pressure in said second mentioned means sufficient to cause discharge of the liquid without substantial loss in the distance to which it may be moved.

In testimony whereof I affix my signature.
WADE H. WINEMAN.
